JAMES E. WILLIAMS AND WILLIAM L. WILLIAMS, OF WILLIMANTIC, CONNECTICUT.

ADJUSTABLE THREAD-GUIDE.

1,281,887.

Specification of Letters Patent. Patented Oct. 15, 1918.

Application filed December 27, 1915, Serial No. 68,616. Renewed February 26, 1918. Serial No. 219,542.

To all whom it may concern:

Be it known that we, JAMES E. WILLIAMS and WILLIAM L. WILLIAMS, both citizens of the United States, and residents of Willimantic, in the county of Windham, in the State of Connecticut, have jointly invented a certain new and useful Improvement in Adjustable Thread-Guides, of which the following is a specification, reference being had 10 to the accompanying drawings.

This invention relates to guides for use in connection with the spooling of thread and, more particularly, with the winding of finished thread upon the spools upon which 15 the said thread is to be marketed; our immediate object being to provide an improved form, and construction, of guide which will be more serviceable than those now in common use, without being objectionably expensive to produce.

In order to explain our said invention clearly we have provided the annexed drawings, in which Figures 1 and 2 are respectively, side and plan views of a thread guide embodying our present improvements and Fig. 3 is an elevation of the same with the front plate removed to disclose the position of the guide disk, as well as the relative position of the guide channel member 16. 25 Fig. 4 is a plan view of the device of Figs. 1 and 2 with the said guide channel member removed in order to show more clearly the manner of locating and clamping the guide disk between the side-plates.

Fig. 5 is a side view of the guide disk and of the guide channel member, and in the Fig. 6, we have shown, relatively enlarged, an edge view of the guide disk for the purpose of illustrating in the circumferential 35 edge portion of said disk, the annular groove which serves to guide the thread as it is being rapidly laid upon the spool and also the adjacent parallel grooves which, meanwhile, iron down, so to speak, the coils of thread 40 last laid upon the spool, as we will explain more in detail later.

In Figs. 7 and 8 we have illustrated, by side and top views, a slightly modified and simplified form of adjustable thread guide. 50 Fig. 9 is a transverse section on line 9—9 of Fig. 7.

Briefly described, our improved guide consists of a forked holder having adjustably clamped therein a guide disk formed with 55 an annular groove, and in concentric relation thereto, a relatively adjustable guide

member formed as a segment of an exteriorly channelled annulus.

Referring to the annexed drawings, the numeral 10 indicates the frame or holder of our improved guide, the same being, by preference, formed of two sections of steel punched and swaged to the desired form and welded, or otherwise fixedly secured, together, one end portion of each half section 60 being bent outward to provide space in which may be located a disk 11 which is bored centrally and is clamped fixedly in the bifurcated end portion of the holder 10 by means of a screw or bolt 12. 70

As stated above, the disk 11 is formed with an annular groove which is denoted by the numeral 13 (see Fig. 6); said groove being located in the middle of the circumferential face of the disk and between a plurality of 75 similar grooves 14 and 15.

Located in concentric relation to the described disk 11 is an exteriorly channelled annulus 16 which may be clamped in its adjusted position between the sides of the 80 holder by the clamping screw 12, as seen in Fig. 7 of the drawings, or may be clamped by means of special screws 17 as illustrated in Figs. 1 and 2.

When in service our described guide is 85 located with respect to the spool, upon which the thread is being wound, about as seen in Figs. 1 and 2, that is to say the perimeter of the spool body, or the last coil of thread laid thereon, is in contact with the guide disk 11 90 at the point where the outer end of the annulus 16 is located, as will be understood by reference to Figs. 1 and 2 of the drawings. The thread is directed first along the curved channel in the annulus 16, thence downward 95 between the spool and the grooved disk 11 and thence around the spool as indicated by dotted line in Fig. 3 of the drawings, the bottom of the channel in the annular segment being exactly in line with the central groove 100 13 in disk 11 and being backed off, so to speak, as seen in Fig. 3, so that, in effect, the channel in the segment 16 leads the thread into the said groove 13 which holds the thread against lateral deflection, or displacement, while the complete guide travels forth and back along the spool, in the customary manner, and thus lays the thread upon the spool in successive coils with absolute regularity and under a uniform tension. 105

While the thread is thus being properly and positively guided to coil it upon the

spool, the grooves 14—15 at the sides of the central, or guide, slot 13 engage the coils of thread last laid with a tendency to smooth down, with a mangling and polishing effect, 5 the said coils of thread last laid.

Keeping in mind the fact that the disk 11 is clamped against rotation, it will be understood that all wear of said disk resulting from the rapidly traveling thread will be 10 limited to the point where the said disk receives the thread from the segment 16 and directs it to the spool and, when such wear occurs, it is only necessary to ease back the clamping screw 12 and then turn the disk 11 slightly and re-clamp it in its adjusted 15 position, thus providing, with practically no delay and with no expense, a new guide slot 13.

In practice we find that the guide disk 11 may be adjusted to new positions of effectiveness about ten times before the entire groove 13 becomes worn and no longer useful, thus enabling our described guide to be used at least ten times as long as the ordinary forms of grooved guides in which no provision is made for adjustment of such guides to new (that is to say, unused) positions. With equal facility the channeled segment 16 may be adjusted in a curved path 30 around, or upon, the disk 11, by easing back the central clamping screw 12, or the special clamping screws 17, as the case may be.

Referring now to Fig. 6 it will be seen that the circumferential edge portions of 35 disk 11 are reduced slightly in diameter and chamfered as at 18, this construction being specially provided for an important purpose, to wit, to prevent the said disk from cutting into, or otherwise defacing, or injuring, the diagonal end walls of the spool as the guide travels from end to end of said spool and contacts with the spool; the described construction of the disk at 18 being such that said disk will readily ride upward 40 along the said diagonal walls of the spool instead of defacing or marking said walls.

Copies of this patent may be obtained for five cents each, by addressing the "Commissioner of Patents, Washington, D. C."

In effect, the channeled segment 16 serves to direct the thread to the groove 13 in disk 11 and the said disk serves to guide the thread and lay it in even coils upon the spool and, at the same time, the side grooves 14—15 serve to iron down the coils previously laid by groove 13.

In the form of holder 10 illustrated in Figs. 7 and 8, the two portions are of the same design so that they may be produced by one punch and die and so that the segment 16 may be clamped between the forked end portion of said holder by the same screw 12 which is used to clamp the disk 11 in its operative position.

Our described device may be cheaply produced, it may be quickly adjusted and we have demonstrated by repeated trials that it performs its work effectively and satisfactorily.

Having thus described our invention we claim as new and wish to secure by Letters Patent:

1. The improvement in thread guides 70 which comprises a holder, a circumferentially grooved guide disk rotatably mounted in said holder, and means for clamping the said disk in its adjusted position; said disk being formed with a central circumferential 75 guide groove and with parallel side grooves.

2. The improvement in thread guides which comprises a holder, a guide disk rotatably mounted in said holder, and means for clamping, said disk in its operative position; said disk being formed with a circumferential guide groove and with chamfered edge portions.

3. The improvement in thread guides which comprises a holder, a circumferentially grooved guide disk mounted in said holder, a channeled segment concentric with the said disk, and means for clamping the said guide disk and segment in their operative positions.

JAMES E. WILLIAMS.
WILLIAM L. WILLIAMS.
